UNITED STATES PATENT OFFICE.

SAMUEL J. SCHLAPPICH, CHARLES R. WARD, AND JAMES S. SHERIDAN, OF MCKEESPORT, PENNSYLVANIA.

TRAY.

No. 930,890.

Specification of Letters Patent.

Patented Aug. 10, 1909.

Application filed May 18, 1908. Serial No. 433,390.

To all whom it may concern:

Be it known that we, SAMUEL J. SCHLAPPICH, CHARLES R. WARD, and JAMES S. SHERIDAN, citizens of the United States of 5 America, residing at McKeesport, in the county of Allegheny and State of Pennsylvania, have invented certain new and useful Improvements in Trays, of which the following is a specification, reference being had 10 therein to the accompanying drawing.

This invention relates to a tray particularly designed for supporting ice cream cones or cornucopias filled with refreshments.

The primary object of our invention is to 15 provide a simple and inexpensive tray for supporting a plurality of cones in a vertical position.

A further object of our invention is to provide a tray constructed of two pieces of material, one piece of material being card board 20 bent to provide the body of the tray, while the other piece of material is a piece of wire bent to provide a handle for the tray.

The detail construction entering into our 25 invention will be presently described and then specifically claimed.

Referring to the drawings forming a part of this specification, Figure 1 is a perspective view of our tray, Fig. 2 is a plan of a piece of 30 material forming the body of the tray, and Fig. 3 is a cross sectional view of our tray.

To put our invention into practice, we provide a rectangular piece of card board, paperoid or similar material with openings 35 1 and 2, the openings 1 being arranged in two rows with the openings of one row staggered with relation to the openings of the other row. The openings 2 are similarly arranged, and are approximately twice the 40 diameter of the openings 1. The piece of card board is bent upon the dotted lines 3 to provide a rectangular structure having a top 4 with the openings 2 formed therein, a bottom 5 with the openings 1 formed therein, 45 and side walls 6 and 7, said side wall 7 being formed with overlapping longitudinal edges of the piece of card board. These overlapping edges can be adhesively secured together or riveted as may be desired. The 50 openings 1 are thus arranged beneath the openings 2 whereby a cone 8 can be placed in said openings and supported by the edges thereof, as clearly shown in Fig. 1 of the drawings.

In order that the rectangular structure 55 can be easily carried, we provide the same intermediate the ends thereof with a wire handle 9, the vertical portions 10 of said handle extending through slots 11 provided therefor in the top and bottom of the structure adjacent to their edges, whereby the hook shaped ends 12 of said handle can engage the lower edges of the side walls 6 and 7 as best shown in Fig. 3 of the drawings.

It is apparent that we have devised a novel 65 tray that can be advantageously used in parks, picnics and places where a large number of people are to be served with cones containing icecream or a refreshment.

We reserve the right to use a suitable material for forming the body of the tray and to increase the capacity thereof from that shown in the accompanying drawing.

Having now described our invention what 75 we claim as new, is:

A device of the class described formed from a single sheet of material folded to provide an open ended rectangular box embodying a top, a bottom, and side walls, the top and bottom walls having alining openings, said openings in the top wall being of greater diameter than those in the bottom, one of the side walls of said box formed from the free meeting edges of the material which overlap each other and are secured together, 80 the said top and bottom walls further provided with transverse slots adjacent the upper and lower corners of the box, the slots in the bottom wall being in transverse alinement with each other and the slots in the top 85 wall being in transverse alinement with each other, and a handle formed from a piece of wire bent to provide a bail having its vertical arms extending through said slots in the top and bottom walls of the box, and having the 90 free ends of said arms bent to provide hooks 95 engaging the lower corners of the box.

In testimony whereof we affix our signatures in the presence of two witnesses.

SAMUEL J. SCHLAPPICH.
CHARLES R. WARD.
JAMES S. SHERIDAN.
